Inventor:

UNITED STATES PATENT OFFICE.

AUGUSTIN M. PRENTISS, OF FORT CASWELL, NORTH CAROLINA, ASSIGNOR OF ONE-HALF
TO DOUGLASS E. BULLOCH, OF WASHINGTON, DISTRICT OF COLUMBIA.

CARBURETER.

1,329,308.

Specification of Letters Patent. Patented Jan. 27, 1920.

Application filed February 19, 1916. Serial No. 79,379.

To all whom it may concern:

Be it known that I, AUGUSTIN M. PRENTISS, a citizen of the United States, residing at Fort Caswell, in the county of Brunswick and State of North Carolina, have invented 5 certain new and useful Improvements in Carbureters, of which the following is a specification, reference being had therein to the accompanying drawing.

10 This invention relates to improvements in carbureters and has for its object:

First: To provide an improved system of this nature wherein the liquid fuel is fed into the mixing chamber by a positive pressure which varies with the demands of the 15 engine.

Second: To provide an improved system of this character wherein the liquid fuel feed is virtually independent of the aspirating or 20 induction effects of the air column passing the fuel nozzles.

Third: To provide an improved system of this kind wherein the pressure on the liquid fuel is gradually diminished as the speed of 25 the engine increases so as to neutralize the common tendency of devices now on the market to increase the feed of liquid fuel faster than the volume of air taken in as the speed of the engine increases.

30 Fourth: To provide an improved device that is self-priming when starting; that is a device which will automatically and positively furnish a charge of highly enriched mixture on the first suction stroke of the 35 motor without the usual manual operation of flooding or priming.

Fifth: To provide an improved system which will furnish a relatively rich mixture at low speeds either on nearly open or nearly 40 closed throttle to prevent stalling, and which will gradually reduce the richness of the mixture as the speed of the engine increases.

Sixth: To provide an improved system of 45 this nature having means for supplying air under pressure to the liquid fuel column within the nozzle to break up the liquid column before it issues from the mouth of the nozzle, thereby forming a spray independently of any condition of air currents in the 50 mixing chamber.

Seventh: To provide an improved device of this nature having means of supplying mixture of air and liquid fuel which shall

vary in quality only between certain relatively narrow predetermined limits and in 55 quantity with the demands of the engine.

The invention, with other objects and advantages thereof and the particular construction, combination and arrangement of parts comprising the same, will be understood from the following detailed description when considered in connection with the accompanying drawings forming a part hereof and wherein I have illustrated one embodiment of the invention. 65

In the drawings:

Figure 1 is a central vertical section of a device constructed in accordance with the present invention;

Fig. 2 is a section on the line 2—2 of 70 Fig. 1;

Fig. 3 is a section on the line 3—3 of Fig. 1, on an enlarged scale;

Fig. 4 is a side elevation;

Fig. 5 is a section on the line 5—5 of 75 Fig. 1;

Fig. 6 is a detailed sectional view, on an enlarged scale of one of the nozzle structures;

Fig. 7 is a diagrammatic view to indicate the relative areas of one of the air inlet and 80 mixture outlet ports, and of the cross section of the throat of the mixing chamber. The area of the air inlet port is marked B, and the area of the mixture outlet port is marked A, and the area of the cross-section of the mix- 85 ing chamber is marked D.

The invention broadly comprehends means for applying pressure upon the top of the liquid fuel in the reservoir whereby the liquid fuel is fed into the mixing chamber by 90 a positive pressure greater than atmospheric which varies with the demands of the engine, the pressure being continuous and gradually diminishing as the speed of the engine increases. More particularly the in- 95

vention contemplates means for this purpose including valve mechanism for varying the cross sectional areas of the air inlet and mixture outlet simultaneously with a pro- 100 gressively diminishing difference, a mem- ber adapted to be moved through the influence of the difference in internal and external air pressures, and a piston or the like arranged to apply pressure upon the top of the liquid fuel in the reservoir and opera- 105 tively connected with said member. The in-

vention further contemplates a valve acting in conjunction with the first mentioned valve mechanism, and operating automatically through the difference in internal and external air pressures to increase the cross sectional area of the air inlet as the speed of the engine increases. As will be appreciated the amount of pressure applied upon the top of the liquid fuel in the reservoir by the piston depends upon the degree of vacuum in the mixing chamber or the difference in internal and external air pressures and this is regulated and gradually diminished through the valve mechanism as the speed of the engine increases, so that at low speeds either on nearly open or nearly closed throttle the pressure on the liquid fuel in the reservoir will be greatest and the pressure gradually diminished as the speed of the engine increases, a relatively rich mixture being furnished on low speeds, and the richness of the mixture being reduced as the speed of the engine increases.

In the drawings, I have illustrated a preferred embodiment of the invention and the particular construction shown comprises a casing having a central longitudinally extending chamber 1 constituting the mixing chamber and upper and lower annular chambers 2 and 3 surrounding the mixing chamber, the lower chamber 3 serving as the liquid fuel reservoir, and the upper has an outlet chamber from which the mixture is discharged into the engine manifold. The casing is made up of an outer shell 4, an inner cylindrical shell 5 spaced from and arranged concentric with the outer shell, a bottom wall 6 connecting the shells at one end and a top wall 7 closing the shells at their upper ends. 8 is a diaphragm separating the chambers 2 and 3. In the present instance the outer and inner shells 4 and 5, and the bottom wall 6 are shown as integral, and the top 7 is a separate part and detachably secured in place, the top being provided with a threaded portion 9 engaging a threaded portion 10 at the upper end of the outer shell 4. The diaphragm 8 is also detachably secured in position, the diaphragm having a threaded collar 11 engaging a threaded portion 12 on the upper end of the inner shell 5. The diaphragm has a depending flange 13 to fit within the outer shell, the outer marginal portion of the diaphragm fitting against the upper end of the outer shell and being engaged at its upper side by a flange 14 on the top 7, this particular arrangement affording convenient access to the interior of the casing. The inner shell 5 is provided with an enlarged portion 5' at its upper end, and the walls of the inner shell 5 at the lower end thereof are shown diverging to provide an enlarged inlet portion.

65 The valve mechanism for varying the

cross sectional areas of the air inlet and mixture outlet simultaneously with a progressively diminishing difference, in the particular embodiment of the invention illustrated in the drawings, comprises the following 70 construction and arrangement of parts.

Rotatably fitting the interior of the inner shell is a hollow cylindrical valve member having an enlarged portion 16 at one end fitting within the part 5' of the inner shell, 75 an enlarged part 22 extending below the bottom wall 6 of the shell, and intermediate portions 15 and 22', the valve member being shown as made up of three sections, the intermediate portion 22', and the enlarged 80 portion 22 of the valve member being formed as separate parts, the former being detachably connected by a thread connection 23 with the intermediate portion 15, and the enlarged portion 22 connected with 85 the intermediate portion 22' by a detachable thread connection 23'. The enlarged portion 16 of the valve member has a closed upper end 17 from which projects a stem 18. One end of the valve member fits against 90 the under face of the top 7, the stem 18 extending through an opening 19 in the top. A nut 19^a engages a threaded portion 20 of the stem, and a washer 21 interposed between the nut and the upper face of the top 95 is provided to support the valve member in place.

The enlarged portion 5' of the inner shell 5 is provided with a series of ports 24, leading from the mixing chamber into the upper chamber 2, said chamber 2 being adapted to be in communication through an opening 2' with the manifold of an internal combustion engine. The upper part 16 of the valve member is provided with a series of ports 25 105 adapted to register with ports 24 to regulate the mixture outlet.

Slidably fitting the interior of the lower part 22 of the valve member is a cylindrical cup-shaped piston valve 26, which is provided with a series of ports 27, and the part 22 of the valve member has a series of ports 28 adapted to register with the ports 27 to permit air to enter the mixing chamber. The relative size, shape, and arrangement of the respective sets of outlet ports 24-25 and inlet ports 27-28, are such, that upon rotation of the valve member, the ports of each set will be simultaneously brought into register and the cross sectional areas 110 of the air inlet and mixture outlet through the respective sets of ports will be varied simultaneously with a progressively diminishing difference, the cross sectional area of the mixture outlet being always greater 115 than that of the free air inlet. Referring particularly to Fig. 7 of the drawings, the outlet ports 24-25 are shown rectangular in shape, the area of the outlet ports being 120 designated by A. The combined portage of 130

these mixture outlet ports is equal to the area of the cross section of the throat of the mixing chamber, the latter being indicated and designated D in the figure referred to, there being, in the present instance, four of such ports 24-25. The inlet ports 27-28 are elliptical in shape and are equal in number to the outlet ports 24-25. The cross sectional area of the inlet ports is greater than that of the outlet ports, and the combined areas of the inlet ports is in excess of the area of the cross section of the throat of the mixing chamber. The width of the inlet and outlet ports is the same, but the area B (indicated by dotted lines in Fig. 7) equals the area of one of the outlet ports, the added strips at top and bottom designated C indicating the difference in area of the inlet ports and outlet ports. The rotary adjustment of the valve member is adapted to be manually controlled, the stem 18 of the valve having a crank arm 29 for connection with any suitable operating means. As will be understood the enlarged part 5' of the inner shell 5 provided with the ports 24, and the enlarged portion 16 of the valve member provided with the series of ports 25 constitute a valve for regulating the mixture outlet, and the throttling valve for the engine.

The valve 26 is adapted to slide longitudinally within the part 22 to bring the ports 27-28 into register to vary the cross sectional area of the air inlet in a direction at right angles to the direction in which the cross sectional area of the air inlet is varied by the rotary adjustment of the valve member. The valve 26, which is exposed at its upper side to the engine suction and at its under face through the opening 30 in the bottom of the part 22 to atmospheric pressure, acts automatically through the difference in the internal and external air pressures. The excess area of the inlet ports 27-28 over the mixture outlet ports 24-25 afforded by the added areas C at the top and bottom of the inlet ports 24-25, provides for a lowering of the valve 26 about two thirds of its total lift, when the inlet and outlet ports have been opened as far as possible by the rotary adjustment of the valve member, and when this relation exists, at open throttle, the areas of the air inlet and mixture outlet through the respective ports are nearly equal.

31 designates the annular piston arranged to work in the liquid fuel reservoir to apply pressure upon the top of the body of liquid fuel. The piston 31 may be provided with any suitable form of packing, not shown, and also with annular depending flanges 32 and 33 entering the body of liquid fuel in the reservoir and forming a seal against the escape of air from the under side of the piston. A suitable vent opening 34 is provided

in the wall of the outer shell 4 above the piston. The piston 31 is operatively connected with the piston valve 26 so that upon the movement of the valve 26 in one direction, a corresponding movement will be transmitted to the piston 31 in the opposite direction. The connection between the piston 31 and the piston valve 26 comprises a stem 35 secured to the piston valve, levers 36 and links 37. The levers 36, which extend through small openings 38 in the inner shell 5 and slots 39 in the valve 15 are pivoted intermediate their ends to ears 40 on the inner shell, connected at their outer ends by links 37 with the piston 31 and at their inner ends to a head 29^a of the stem 35, said head being provided with pin 41 engaging slots 42 in the inner ends of the levers. The links 37 work through openings 43 in the diaphragm 8, and any suitable form of packing, not shown, may be provided for the openings. The head 29^a has a detachable screw thread connection with the upper end of the stem and is provided with cross arms 44 extending through slots 45 in the valve 15 and engaging grooves 46 formed in the inner shell 5, the valve 26 being thus held fixed from rotation while permitted to move longitudinally.

The valve member carries a plurality of nozzles 47 arranged at separated points thereabout to feed inwardly into the mixing chamber. The nozzles 47 comprise an outer air jet pipe 48 and an oil tube 49 extending centrally within the air pipe. The inner shell 5 is provided with a series of oil outlets a, b, c, d, arranged at different points about the shell, the arrangement of the oil outlets and oil pipes 49 being such that as the valve 15 is turned to bring the air inlet ports 24, 25 and the mixture outlet ports 27, 28 into register, the oil tubes will be simultaneously with the air ports brought into register in succession with the oil outlets 50 to suit the demand of the engine. The oil outlets a, b, c, d, are preferably formed as shown extending tangentially through the wall of the shell 5, and the inner mouth of each tube is made of such width that the mouth of tube a is the smallest, that the tube b is substantially twice the width of a, that of c substantially three times the width of a, and d is substantially four times the width of a. Thus in turning the valve member 15, in a counter clockwise direction, d is brought into register first, then d and c; then d, c, and b; and finally at full opening d, c, b and a are all in register, one wall of each oil outlet being curved as shown to obtain a very fine outlet orifice at first as the pipe is gradually brought into register with the outlet, the outlet being gradually increased in size as the jet pipes are brought in full register with the outlets.

Means is provided for supplying air un-

der pressure to the liquid fuel column within the oil pipes 49 in the nozzles to break up the liquid column before it issues from the mouth of the nozzles thereby forming a spray independently of any condition of air currents in the mixing chamber. In the present instance, auxiliary air supply conduits 52 are provided for supplying air to the nozzles, said conduits communicating with the outer air spray pipes 47 of the nozzles, and a motor operated pump 53 is provided to supply air under pressure to said auxiliary conduits, the pump being connected to the auxiliary air supply conduit 10 by a connection 54.

Any suitable means may be provided for maintaining liquid fuel in the reservoir 3 at a substantially constant predetermined level. The means for this purpose illustrated in the drawings comprises a float 55 operatively connected with a cutoff valve 56 interposed in the oil supply conduit 57. 59 designates a pump connected with the oil supply conduit for supplying oil under pressure to the reservoir, said pump being adapted to force the oil through the conduit at a pressure at least equal to the maximum pressure that is applied to the top of the liquid in the reservoir by the piston 31. The pump 59 may be of any approved form, that illustrated being the conventional type of force pump having the check valves 61, 62. 63 designates a by-pass connection for the pump. Any suitable form of motor may be provided to operate the air pump and oil pump, but preferably an electric motor, not shown, is provided for this purpose.

The operation of the device is as follows: With the engine at rest, the valve 15 and the piston valve 26 are in the positions indicated in Fig. 1 of the drawings, the ports 24 and 25 and the ports 27 and 28 being completely out of register, said last mentioned ports being out of alignment longitudinally but slightly aligning with each other transversely. In starting, the valve 15 is turned a slight distance to bring the ports 24-25 partially into register and the ports 27 and 28 into register to a small extent. Now as the engine is turned over, on the out stroke of the engine piston, the piston valve 26 will be caused to move upward by the difference in the internal and external air pressures, the piston 31 being forced downwardly and pressure is applied upon the top of the liquid fuel in the reservoir, to force oil out through the oil outlet and oil tube of the nozzle, which at that time is in register. It will be understood that at this time the air and oil pumps have been set in operation, and the air supplied to the fuel nozzle under pressure serves to break up the liquid column before it issues from the mouth of the nozzle, so that the liquid fuel is forced out in a very fine spray independently of any

condition of air currents in the mixing chamber. As the valve 26 rises, the ports 27 and 28 are brought further into registration, and as the valve 15 is rotated to bring the ports 24-25 and 27-28, into registration as fully as possible, the difference of cross sectional areas of the air inlet and mixture outlet is gradually diminished with a consequent lessening of the difference of internal and external air pressures and the pressure applied upon the top of the liquid by piston 31 until, at open throttle, the area of the air inlet and mixture outlet are nearly equal and the superposed pressure on the liquid fuel in the reservoir is reduced to nearly atmospheric pressure, there being, however, always some difference in pressure. Referring particularly to Fig. 7 of the drawings, it will be seen that the inlet ports are elliptical in cross section whereas the outlet ports are rectangular, the horizontal dimension of each being the same but the vertical dimension of the inlet being greater than that of the outlet. Therefore during the first stages of opening of the inlet and outlet valves, the rectangular area of the outlet ports in register is greater than the corresponding segmental area of the inlet ports in register, and a condition of vacuum in the mixing chamber is established. A further opening of the valves, however, reduces the preponderance of the outlet portage over that of the inlet portage resulting in a decrease of vacuum in the mixing chamber. If now there were no vertical adjustment of the inlet valve 26, a point would be reached, near quarter turning where the area of the inlet port would exactly equal that of the outlet and a condition of steady flow would be set up and the vacuum would be greatly reduced, and if the area of the inlet and outlet ports happened to be each equal to that of the cross section of the mixing chamber at that point, the vacuum would practically vanish. But this reduction in the intensity of the vacuum results in a lowering of the inlet valve member which reduces the inlet portage, so that a point where the inlet and outlet are exactly equal can never be reached with the result that there is always some vacuum in the mixing chamber. It will thus be understood that the greatest degree of vacuum in the mixing chamber is when the preponderance of the outlet ports over the inlet ports is a maximum, that is, at the beginning of the opening of the valves, and that this vacuum is gradually reduced as the preponderance is reduced, namely, as the valves are opened. It therefore follows that the piston valve 26 will be in its uppermost position during the initial stages of the opening of the valves and will gradually descend as the vacuum is relieved, that is, as the valves are opened,

consequently the superimposed air pressure upon the oil in the float chamber will be a maximum during the initial stages of the opening of the valves and will be gradually lessened as the valves are manually opened, reaching its minimum at full opening. At open throttle the piston valve has lowered about two thirds of its total lift, the pressure at the under side of the piston 31 serving to force the piston upwardly as the pressure is relieved from the upper side thereof. The valve 26 acting through the difference in the internal and external air pressure serves to further regulate the degree of vacuum in the mixing chamber or the difference in internal and external air pressures, balancing the action of the mechanism to obtain the desired continuous gradually diminishing pressure upon the top of the liquid in the reservoir.

It will be remarked that the invention provides for a lessening of the superimposed air pressure upon the oil feed to counteract the common tendency of all suction operated carbureters to feed an excess of oil on the higher speeds or as the engine speeds up. As is well known, the flow of air does not follow the law of efflux or influx of liquids due to a varying density in its more or less attenuated condition. This difference in the efflux of air and liquids causes a departure from any fixed ideal ratio of the two at any given speed, or degree of difference of internal and external pressures, and therefore any device in which the feed of oil is made to depend directly upon the velocity of the current of air passing the fuel outlet must necessarily fail to maintain a fixed ideal ratio between the two as the suction and therefore the velocity of the air current is increased. The present invention accomplishes this maintenance of a fixed ideal ratio by first applying a superimposed pressure upon the liquid fuel in the fuel reservoir, thus making the conditions at the fuel outlet of the nozzle virtually independent of the air current in the mixing chamber, and then gradually decreasing the superimposed pressure upon the fuel feed as the speed of the engine increases, until at open throttle this superimposed pressure is reduced to nearly atmospheric pressure, but never quite so.

It will also be observed that provision is made for increasing the volume of the mixture by bringing a plurality of fuel ports progressively into action simultaneously with an opening of the air inlet ports, but the ratio of air flow to fuel flow is controlled by a system of balanced pressures whereby the volume of the mixture can be increased without altering the quality or departing from a fixed ideal ratio of air to oil.

It will be understood that the term "positive pressure" in the specification and claims

is used to mean a pressure greater than atmospheric.

I desire it to be understood that changes and modifications in the particular form of the device illustrated in the drawings, as 70 will appeal to those skilled in the art may be made without departing from the broad principles of the invention.

What I claim is:

1. In a carbureter, a mixing chamber, a 75 liquid fuel reservoir, means for maintaining liquid fuel therein at a substantially constant predetermined level, means for maintaining a positive pressure always greater than atmospheric upon said liquid 80 fuel and means for varying the pressure upon said liquid fuel inversely as the pressure in the mixing chamber.

2. In a carbureter, an outlet chamber, a liquid fuel reservoir, means for maintaining 85 liquid fuel therein at a substantially constant predetermined level, means for maintaining a positive pressure always greater than atmospheric upon said liquid fuel and means to vary the pressure upon 90 said liquid fuel directly as the vacuum in the outlet chamber.

3. In a carbureter, a mixing chamber, a liquid fuel reservoir, means for maintaining liquid fuel therein at a substantially 95 constant predetermined level, means for maintaining a positive pressure always greater than atmospheric upon said liquid fuel and means to vary the pressure upon said liquid fuel inversely as the pressure 100 in the mixing chamber, and in a constantly decreasing ratio as the pressure in said chamber increases.

4. A carbureter comprising an outlet chamber, a liquid fuel reservoir, means for maintaining liquid fuel therein at a substantially constant predetermined level, means for maintaining a positive pressure always greater than atmospheric upon said liquid fuel, and means to vary this pressure 105 directly as the vacuum in the outlet chamber and in a constantly decreasing ratio as the vacuum in said chamber increases.

5. In a carbureter, an air inlet port of conic cross section, a plurality of fuel inlets, 115 a mixture outlet, and means consisting of a single rotary valve member for varying the cross sectional area of said inlets and outlet simultaneously.

6. In a carbureter, an air inlet port of 120 conic cross section, a mixture outlet port, and means consisting of a single rotary valve member to vary the cross sectional areas of said inlet and outlet ports simultaneously with a progressively diminishing difference 125 as said ports are opened.

7. In a carbureter, an air inlet, a liquid fuel reservoir, means to vary the cross sectional area of said inlet, and means associated with said first mentioned means for 130

- varying the pressure upon the fuel in said reservoir as the cross sectional area of said inlet is varied.
8. In a carbureter, a mixing chamber having an air inlet and a mixture outlet, a fuel feeding nozzle associated with the mixing chamber, a liquid fuel reservoir, means for maintaining liquid fuel therein at a substantially constant predetermined level, means for supplying pressure upon the liquid fuel in the reservoir directly as the vacuum in the mixing chamber, and means for supplying air under pressure to the fuel feeding nozzle.
9. In a carbureter, a liquid fuel reservoir, means for maintaining liquid fuel therein at a substantially constant predetermined level, said means including a float and valve mechanism for the reservoir, and a pump for supplying liquid fuel under pressure to the reservoir, and means for supplying pressure upon the liquid fuel in the reservoir directly as the vacuum in the mixing chamber.
10. In a carbureter, a liquid fuel reservoir, means for maintaining liquid fuel therein at a substantially constant predetermined level including a motor operated pump for supplying liquid fuel under pressure to the reservoir, and means for supplying pressure upon the liquid fuel in the reservoir directly as the vacuum in the mixing chamber.
11. In a carbureter, a mixing chamber having an air inlet and a mixture outlet, means for varying the cross sectional areas of said inlet and outlet simultaneously, a liquid fuel reservoir, means for maintaining liquid fuel therein at a substantially constant predetermined level, and means for supplying pressure upon said liquid fuel directly as the vacuum in the mixing chamber.
12. In a carbureter, a mixing chamber having an air inlet and a mixture outlet, means for varying the cross sectional areas of the inlet and outlet simultaneously with a progressively diminishing difference, a liquid fuel reservoir, means for maintaining liquid fuel therein at a substantially constant predetermined level, and means for supplying pressure upon the liquid fuel in the reservoir directly as the vacuum in the mixing chamber.
13. In a carbureter, a mixing chamber having an air inlet and a mixture outlet, a fuel feeding nozzle associated with the mixing chamber, a liquid fuel reservoir, means for maintaining liquid fuel therein at a substantially constant predetermined level, means providing pressure upon the liquid fuel in the reservoir directly as the vacuum in the mixing chamber, means for varying the cross sectional areas of said inlet and outlet simultaneously, and means for supplying air under pressure to the fuel feeding nozzle.
14. In a carbureter, a mixing chamber having an air inlet and a mixture outlet, a fuel feeding nozzle associated with the mixing chamber, a liquid fuel reservoir, means for maintaining liquid fuel therein at a substantially constant predetermined level, means providing pressure upon the liquid fuel in the reservoir directly as the vacuum in the mixing chamber, means for varying the cross sectional areas of the air inlet and mixture outlet simultaneously with a progressively diminishing difference, and means for supplying air under pressure to the fuel feeding nozzle.
15. In a carbureter, a liquid fuel reservoir, means for maintaining liquid fuel therein at a substantially constant predetermined level, means for maintaining a positive pressure always greater than atmospheric upon said liquid fuel, a mixing chamber and means actuated automatically by the difference of pressures internal and external of said mixing chamber for varying the pressure upon the liquid fuel in the reservoir inversely as the pressure in the mixing chamber.
16. In a carbureter, a liquid fuel reservoir, means for maintaining liquid fuel therein at a substantially constant predetermined level, and means acting automatically to always maintain a pressure greater than atmospheric and for varying the pressure upon the liquid fuel in the reservoir inversely as the pressure in the mixing chamber, said means including a piston operated by the difference in the internal and external air pressures.
17. In a carbureter, a carbureter or mixing chamber, having an air inlet and a mixture outlet, a liquid fuel reservoir, means for maintaining liquid fuel therein at a substantially constant predetermined level, and means for varying the pressure upon the liquid fuel in the reservoir inversely as the pressure in the mixing chamber, said means including a piston operating automatically by the difference in internal and external air pressures, and a valve controlling the air inlet and operatively connected with said piston.
18. In a carbureter, an air inlet port of conic cross section, manually operable means for varying the cross sectional area of the inlet in one direction, and automatic means acting directly through the difference in internal and external air pressures for varying the cross sectional area of said inlet in another direction.
19. In a carbureter, an air inlet port of conic cross section, manually operable means for varying the cross sectional area of the inlet in one direction, and automatic means acting directly through the difference of internal and external air pressures for varying the cross sectional area of said inlet.

inlet in a direction at right angles to the first mentioned direction.

20. In a carbureter, an air inlet, a mixture outlet, manually operable means for varying the cross sectional areas of the inlet and outlet simultaneously, and means acting automatically through the difference in internal and external air pressure for varying the cross sectional area of the air inlet.

10 21. In a carbureter, an air inlet, a mixture outlet, manually operable means for varying the cross sectional areas of the inlet and outlet simultaneously with a progressively diminishing difference, and means 15 acting automatically through the difference in internal and external air pressures to vary the air inlet.

22. In a carbureter, a mixing chamber having an air inlet and a mixture outlet, a 20 liquid fuel reservoir, means for maintaining liquid fuel therein at a substantially constant predetermined level, and means for varying the pressure upon the liquid fuel in the reservoir inversely as the pressure in 25 the mixing chamber, said means including a piston acting automatically through the difference in internal and external air pressures, a piston in the liquid fuel reservoir, and an operative connection between said 30 pistons.

23. In a carbureter, a mixing chamber having an air inlet and a mixture outlet, a liquid fuel reservoir, means for maintaining liquid fuel therein at a substantially 35 constant predetermined level, and means for varying the pressure upon the liquid fuel directly as the vacuum in the mixing chamber, said means including a piston operating automatically through the difference in internal and external air pressures, a rod connected with said piston, a second piston in 40 the liquid fuel reservoir, and a lever pivoted intermediate its ends and connected at opposite ends with said rod and said first mentioned pistons respectively.

24. In a carbureter, a mixing chamber having an air inlet and a mixture outlet, a liquid fuel reservoir, means for maintaining liquid fuel therein at a substantially 50 constant predetermined level, means for varying the cross sectional areas of said inlet and outlet simultaneously with a progressively diminishing difference, and means for varying the pressure upon the liquid fuel in the 55 reservoir inversely as the pressure in the mixing chamber.

25. In a carbureter, a mixing chamber having an air inlet and a mixture outlet, means for varying the cross sectional areas 60 of the inlet and outlet simultaneously with a progressively diminishing difference, a valve operated automatically by the difference in internal and external air pressures, to increase the cross sectional areas of the 65 inlet as the speed of the engine is increased,

a liquid fuel reservoir, means for maintaining liquid fuel therein at a substantially constant predetermined level, and means for supplying pressure upon the liquid fuel in the reservoir directly as the vacuum in the 70 mixing chamber.

26. In a carbureter, a mixing chamber having an air inlet and a mixture outlet, means for varying the cross sectional areas of the inlet and outlet simultaneously in 75 one direction with a progressively diminishing difference, a valve operating automatically by the difference in internal and external air pressures to increase the cross sectional areas of the inlet in a direction at 80 right angles to the first mentioned direction as the speed of the engine increases, a liquid fuel reservoir, means for maintaining liquid fuel therein at a substantially constant predetermined level, and means for supplying 85 pressure upon the liquid fuel in the reservoir directly as the vacuum in the mixing chamber.

27. In a carbureter, a liquid fuel reservoir, a mixing chamber having an air inlet and 90 a mixture outlet, a fuel feeding nozzle comprising an outer air jet pipe, and an oil tube extending within the said air jet pipe and communicating with the oil reservoir, means for supplying air under pressure to the air 95 pipe of the nozzle, means for maintaining liquid fuel in the reservoir at a substantially constant predetermined level, means for supplying pressure upon the liquid fuel in the reservoir directly as the vacuum in the mix- 100 ing chamber.

28. In a carbureter, a mixing chamber having an air inlet, a fuel inlet, and a mixture outlet, means for varying the cross sectional areas of said inlets and outlet simultaneously, and varying the cross sectional areas of the air inlet and the mixture outlet with a progressively diminishing difference, a liquid fuel reservoir, means for maintaining liquid fuel therein at a substantially constant 105 predetermined level, and means for supplying pressure upon the liquid fuel in the reservoir directly as the vacuum in the mixing chamber. 110

29. In a carbureter, a mixing chamber 115 having a rectangular shape mixture outlet port, and a tapering air inlet port, a valve provided with a rectangular shape port and with a tapering port, said last mentioned ports corresponding in size and shape and adapted to register respectively with the mixture outlet ports and the air inlet port of the mixing chamber, the valve being adapted to be adjusted to simultaneously bring the respective sets of ports into register for varying the cross sectional areas of the air inlet and mixture outlet simultaneously with a progressively diminishing difference, a liquid fuel reservoir, means for maintaining liquid fuel therein at a substantially con- 120 125 130

stant predetermined level, and means for varying the pressure upon the liquid fuel in the reservoir inversely as the pressure in the mixing chamber.

5 30. In a carbureter, a mixing chamber having a rectangular shape mixture outlet port, and an elliptical shape air inlet port, a valve provided with a rectangular shape port and an elliptical shape port, said ports 10 corresponding in size and shape and being adapted to register respectively with the mixture outlet port and the air inlet port of the mixing chamber, the valve being adapted to be adjusted to simultaneously bring the 15 respective sets of ports into register to vary the cross sectional areas of said inlet and outlet simultaneously with a progressively diminishing difference, a liquid fuel reservoir, means for maintaining liquid fuel 20 therein at a substantially constant predetermined level, and means for varying the pressure upon the liquid fuel in the reservoir inversely as the pressure in the mixing chamber.

25 31. In a carbureter, a mixing chamber having a plurality of rectangular shape mixture outlet ports and a plurality of elliptical shape air inlet ports, a valve provided with a plurality of rectangular shape ports 30 and with a plurality of elliptical ports, the ports corresponding in shape and size and being adapted to register respectively with the mixture outlet ports and inlet ports of the mixing chamber, the combined portage 35 of the mixture outlet ports being equal in area to cross section of the mixing chamber, said valve being adapted to be adjusted to simultaneously bring the respective sets of 40 ports into register to vary the cross sectional areas of the inlet and outlet simultaneously with a progressively diminishing difference, a liquid fuel reservoir, means for maintaining liquid fuel therein at a substantially constant predetermined level, and means for 45 varying the pressure upon the liquid fuel inversely as the pressure in the mixing chamber.

50 32. In a carbureter, a mixing chamber having a plurality of mixture outlet ports, a hollow cylindrical valve rotatably fitting the interior of the mixing chamber said valve being provided with a plurality of ports to register with the said outlet ports of the mixing chamber, and with a plurality 55 of air inlet ports, a valve slidable longitudinally within the hollow cylindrical valve and provided with a plurality of air inlet ports to register with the air inlet ports of said first mentioned valve, the outlet ports 60 being rectangular in shape and the inlet ports being elliptical in shape, the relative size and arrangement of the ports being

such that upon rotary adjustment of the hollow cylindrical valve the air inlet mixture outlet ports will be simultaneously brought 65 into register to vary the cross sectional area of the air inlet and mixture outlet with a progressively diminishing difference, said second mentioned valve being adapted to be operated automatically through the difference 70 in internal and external air pressure to vary the cross sectional area of the air inlet in a direction at right angles to the direction that it is varied by the rotary adjustment of the valve, a liquid fuel reservoir, means for 75 maintaining liquid fuel therein at a substantially constant predetermined level, and means for varying the pressure upon the liquid fuel in the reservoir inversely as the pressure in the mixing chamber.

80 33. In a carbureter, a mixing chamber having a plurality of mixture outlet ports, a hollow cylindrical valve rotatably fitting the interior of the mixing chamber said valve being provided with a plurality of ports to 85 register with the said outlet ports of the mixing chamber, and with a plurality of air inlet ports, a valve slidable longitudinally within the hollow cylindrical valve and provided with a plurality of air inlet ports to 90 register with the air inlet ports of said first mentioned valve, the outlet ports being rectangular in shape and the inlet ports being elliptical in shape, the relative size and arrangement of the ports being such that upon 95 rotary adjustment of the hollow cylindrical valve the air inlet and mixture outlet ports will be simultaneously brought into register to vary the cross sectional area of the air inlet and mixture outlet with a progressively 100 diminishing difference, said second mentioned valve being adapted to be operated automatically through the difference in internal and external air pressures to vary the cross sectional area of the air inlet in a direction at right angles to the direction that it is varied by the rotary adjustment of the valve, a liquid fuel reservoir, means for 105 maintaining liquid fuel therein at a substantially constant predetermined level, a member mounted to slide longitudinally in the mixing chamber and adapted to be operated through the difference in internal and external air pressures, a piston arranged to apply pressure upon the top of the liquid fuel in 110 the reservoir and an operative connection between said member and the piston.

115 In testimony whereof I hereunto affix my signature in the presence of two witnesses.

AUGUSTIN M. PRENTISS.
